MOISTURE CONTROL DEVICE FOR
DUPLICATING MACHINES

Frank Ronald Ford, Birmingham, England

Application March 1, 1946, Serial No. 651,265
In Great Britain January 27, 1945

2 Claims. (Cl. 101—132.5)

1

This invention relates to duplicating machines of the kind wherein a master sheet bearing in reverse script the matter to be reproduced, is mounted on a cylinder with which co-operates a pressure roller, the copy sheets being fed between the cylinder and pressure roller and being moistened by means of a moistening pad before coming into contact with the master sheet on the cylinder.

The present invention is applicable to machines of this type and to constructions in which the pressure roller is above the cylinder, in which case the copy sheet is moistened on its under-side, and to machines in which the pressure roller is below the cylinder, in which case the copy sheets are moistened on their upper sides.

The object of the present invention is to provide improved moistening means for the copy sheets.

According to the present invention, in a machine of the kind specified, I provide a moistening appliance which comprises a reservoir for moistening liquid, a moistening pad mounted in a suitable support, and one or more devices, such as wicks, for feeding the liquid from the reservoir to the pad, means for automatically severing or adjusting or controlling the connection between said feeding means and the pad at the end of each revolution of the cylinder, and one or more auxiliary feeders permanently in engagement with the liquid in the reservoir and with the pad.

Each auxiliary feeder may consist of a length of porous flexible material, such as a single strand of worsted. Each such auxiliary feeder has one end or both ends submerged in the liquid in the reservoir, and the other end, or an intermediate part, located between that side of the pad which is remote from the side to be engaged by the copy sheets and the pad holder. Such auxiliary feeder or feeders are adapted to provide sufficient moisture for starting the machine after a period of rest, and it or they prevent the pad from drying out during a period of rest.

The means for automatically severing, adjusting, or controlling the connection between the main feeding means and the pad, or between the main feeding means and an absorbent member connected to the pad, may include a movable element, and this may be arranged and operated as disclosed in either of prior U. S. A. specifications Pat. Nos. 2,398,888 issued to me on the 23d April 1946 or 540,486 filed 15th June, 1944.

Further, the movable element or elements with which the main feeder or feeders are associated

2

may be operated automatically by a cam or other means moving with the cylinder, and if desired, mounted on the end of the cylinder, and such cam or other means may be connected to the movable element or elements by any suitable form of mechanical gear, such, for instance, as bell crank levers and links. The movable element or elements with which the main feeder or feeders are associated may be in the form

10 of an oscillating clip.

Referring to the drawings:

Figure 1 is a sectional view in side elevation showing a machine to which the present invention has been applied.

15 Figure 2 is a sectional view in side elevation showing the moistening means.

Figure 3 is a sectional front view showing a portion of the moistening means.

Figure 4 is a perspective view showing a portion 20 of the moistening means.

Figures 2, 3 and 4 are drawn to a larger scale than Figure 1.

In the construction illustrated, the invention is applied to a machine having side frames 10 connected by bolts 11 and supporting a cylinder 12 mounted on a spindle 13 rotating in bearings in the frame 10. The cylinder 12 is provided with a clip 14 by which a master sheet may be secured to its periphery, and the cylinder can be rotated by hand or power in the direction indicated.

The pressure roller is shown at 15 and is mounted on a spindle 16.

At one end of the cylinder a flange 17 is provided having a recess 18 engaged by a spring-loaded check device 19 so that the rotation of the cylinder is checked at the end of each revolution.

The copy sheets are fed over a tray (not 40 shown) and between the cylinder 12 and the pressure roller 15, the copy sheets in this construction being moistened on the upper side by a pad 20, the copy sheets being pressed upwardly against this pad by a moistening bar 21 carried by a lever 22 pivoted at 23 and having an oscillating motion imparted to it by a cam 24 on the end of the cylinder 12, the cam 24 contacting a roller 25 carried by a pin 26 secured to the lever 22. The arrangement is such that at the end of each revolution, when the motion of the cylinder 12 is checked by the device 19, the lever 22 is oscillated by the cam 24 to bring the moistening bar 24 away from the pad 20 to allow the sheets to be fed between the pad and the bar 24 to the line of contact between the cylinder

and the pressure roller 15. When the cylinder is rotated, the cam 24 leaves the roller 25, and the moistening bar 21 moves up and presses the copy sheet into contact with the underside of a skin covering 27 on the exposed portion of the pad 20. The levers 22 (there is one at each end of the machine) are spring-loaded in a direction causing the bar 21 to move into contact with the copy sheet as soon as the roller 25 leaves the cam 24.

The moistening appliance comprises a tank 28 supported by the frames 10, the tank having a drain opening normally closed by a removable plug 29.

Each end of the tank is provided with an upwardly extending tubular member 30, the upper ends of which are secured to plates 31 having flanges 32 which can slide into slots 33 provided in the end frames 10.

The two plates 31 are connected by a plate 34 having an opening 35, and the pad 20 is placed against the underside of the plate 34 and is held in position by a channel-shaped member 36 of sheet metal having a portion 37 which embraces one edge of the plate 34.

The plate 34 is provided with a flange 9 which positions the exposed portion of the pad 20.

End plates 38 of angle section are mounted on the tops of the plates 31, and these end plates 38 are connected by a sheet metal cover 39 forming a housing for an oscillating clip 40. This clip is mounted on a tube 41 having a pin 42 fixed in each end, these pins being adapted to oscillate in the end plates 38.

One of the pins 42, as shown in Fig. 3, is provided with two levers 43, 44, which are fixed on the pin. The lever 43 is acted upon by a tension spring 45 fixed to a pin 46 on the plate 31, and the lever 44 engages a lever 47 pivoted at 48 to the side frame 10, and having a second arm 49 provided with a roller 50 acted upon by an eccentric 51 mounted on the spindle 13 of the cylinder.

The clip 40 embraces the tube 41 and is provided with two jaws between which is clamped the centre part 52 of a wick, the end portions 53 of which extend downwardly through the members 30 into the liquid in the tank 28.

The arrangement is such that the lever 47, 49, which is acted upon by the tension spring 54, is oscillated by the eccentric 51 during the rotation of the cylinder, and causes the clip 40 to move the centre part 52 of the wick down into contact with the upper side of the pad 20, and to transfer the moistening liquid thereto. At the end of each revolution of the cylinder, when the check device 19 comes into operation, the centre part 52 of the wick is moved away and out of contact with the pad 20.

The plate 34 is provided in suitable positions with two bridge plates 55, to each of which is secured one end of a feeder 56 which may be made of a single strand of worsted, and each of these feeders extends downwardly through the portion 30 into the liquid in the tank 28. Thus, the pad 20 in addition to being moistened periodically by the part 52 of the main wick, is provided with a constant source of moisture by the feeders 56, this constant source of moisture being always in operation even when the machine is not being used.

Further, I may provide additional feeders 57 each made as a single strand of worsted, each of these feeders having one end in the liquid in the

tank 28 and extending upwardly through one of the parts 30, and thence through an opening 59 into the tube 41, and through an opening 60 in the tube and thus into contact with the portion 52 of the main wick. The main wick is thus constantly fed with moistening fluid, this feed being in operation even when the machine is out of use.

In operation the pad 20 receives moistening liquid while the machine is working during a part of each revolution of the cylinder from the part 52 of the main wick, and the part 52 of the main wick and the pad itself are constantly fed with a small amount of the moistening liquid, both when the machine is in operation and when it is out of use. By this provision the machine can be put into use without delay even if it has been out of use for a considerable period, as the feeders 56 and 57 provide sufficient moisture for starting.

What I claim then is:

1. In a duplicating machine of the kind specified and including a frame in which is supported a rotary cylinder having a clip for holding the master sheet, moistening means for the copy sheets comprising a reservoir for moistening liquid, a support for a moistening pad including a slotted plate, a moistening pad of absorbent material in said support, end plates mounted on said slotted plate, a tube extending between said end plates, pins fixed in the ends of said tube engaging said end plates, one of said pins projecting through one of the end plates, a two-armed lever fixed on said pin, means operated by the rotation of the machine cylinder for oscillating said lever, a clip mounted on said tube, a wick having a portion immersed in the moistening liquid and a portion held in said clip, the wick portion held in said clip being moved by the oscillation of the clip in and out of contact with said moistening member, said wick being held by the clip out of contact with the moistening pad when the machine is stationary, a feeder for moistening liquid having a portion immersed in the liquid in the reservoir and a portion permanently in contact with the moistening pad, and an additional feeder for moistening liquid having a portion immersed in the liquid in the reservoir and a portion in contact with that part of the wick held by the clip, one end of said additional feeder extending through a portion of said tube and into contact with the wick portion held in the clip.

2. In a duplicating machine of the kind specified and including a frame in which is supported a rotary cylinder having a clip for holding a master sheet, moistening means for the copy sheets comprising a reservoir for moistening liquid, a support for a moistening pad, tubes connecting the ends of the reservoir with the ends of the support, a moistening pad of absorbent material in said support, a check device for checking the rotation of the cylinder at the end of each revolution, a clip pivotally mounted near said moistening pad, a lever on the pivot of the clip, an actuating member on the cylinder for rocking said lever, a wick having its ends immersed in the moistening liquid, said wick having portions housed in said tubes, and having a portion held in said clip, the wick portion held in said clip being moved by the oscillation of the clip in and out of contact with said moistening member, said wick being held by the clip out of contact with the moistening pad when the machine is stationary and said check device is in

its operative position, and feeders each having one part immersed in the liquid in the reservoir and having another portion in contact with the wick, one of said feeders extending through each of said tubes.

FRANK RONALD FORD.
